UNITED STATES PATENT OFFICE.

JOHN CORNELIUS O'BRIEN, OF ST. LOUIS, MISSOURI, ASSIGNOR TO EISENSTADT MANUFACTURING COMPANY, OF ST. LOUIS, MISSOURI, A CORPORATION OF MISSOURI.

DESIGN FOR A BRACELET.

51,487.

Specification for Design. **Patented Nov. 13, 1917.**

Application filed October 3, 1917. Serial No. 194,623. Term of patent 7 years.

To all whom it may concern:

Be it known that I, JOHN CORNELIUS O'BRIEN, a citizen of the United States of America, residing at the city of St. Louis, State of Missouri, have invented a new, original, and ornamental Design for a Bracelet, of which the following is a specification, reference being had to the accompanying drawing, forming a part thereof.

Figures 1 and 2 are perspective views of a bracelet, embodying my new design.

I claim:

The ornamental design for a bracelet, as shown.

JOHN CORNELIUS O'BRIEN.
